UNITED STATES PATENT OFFICE.

RASMUS P. ANDERSEN, OF ST. PAUL, MINNESOTA.

VENEERING FOR WALLS OR CEILINGS.

SPECIFICATION forming part of Letters Patent No. 718,593, dated January 20, 1903.

Application filed May 31, 1902. Serial No. 109,611. (No model.)

To all whom it may concern:

Be it known that I, RASMUS P. ANDERSEN, a subject of the King of Denmark, residing at St. Paul, in the county of Ramsey and State 5 of Minnesota, have invented certain new and useful Improvements in Veneering for Walls or Ceilings, of which the following is a specification.

My invention relates to improvements in 10 detachable veneering for walls and ceilings; and it consists in making the veneering in a series of sections or panels and in providing in connection therewith improved means for securing the sections to the main body of the 15 wall or ceiling.

My invention further consists in the features of construction and combination hereinafter particularly described.

In the accompanying drawings, forming 20 part of this specification, Figure 1 is a plan view of the veneering for a wall or ceiling constructed according to my invention, being shown broken away. Fig. 2 is a section on line xx of Fig. 1, and Fig. 3 is a section on 25 line yy of Fig. 1.

In the drawings, A represents the main wall or ceiling, and B represents plates of 30 glass or other desired material. Where the plates B are of glass or of other easily-breakable material, a sheet of felt or other suitable 35 material 2 is first placed against the main wall A to form a backing for the plates B. The plates B are secured in position by buttons 3, which fit over the corners of the plates B, securing-screws 4 passing through said buttons and into the main wall or ceiling A. As shown in Fig. 1, the corners of the plates are cut away to allow the washers 5 to surround the securing-screws 4 intermediate of

the buttons 3 and backing 2, said washers 40 serving to hold the plates slightly separated. The cracks between the plates are covered by strips of molding 6, said strips of molding fitting at their ends against the sides of the buttons 3 and being held in position by brads 7, 45 passing through said strips and between the plates into the main wall or ceiling A.

While I have shown the plates 3 made of glass, I may make them of thin wood or any desired material. Where the strips are made 50 of wood, the backing 2 can be dispensed with.

By the use of my invention the separate panels can be decorated upon their rear or front faces to produce a very artistic wall or ceiling.

Having now described my invention, what I claim as new, and desire to secure by Letters Patent, is—

The combination with a wall or ceiling, of 60 a backing-sheet arranged upon the face thereof, a series of removable sections arranged on the outer face of said backing, the corners of said sections being cut away, washers arranged between the corners of said sections, buttons covering the corners of said sections, 65 securing means passing through said buttons and said washers into the main wall or ceiling, strips covering the cracks between said sections, and securing means passing through said strips and between said sections into said 70 wall or ceiling.

In testimony whereof I affix my signature in presence of two witnesses.

RASMUS P. ANDERSEN.
